OIL WELL APPARATUS

Filed Nov. 16, 1928

UNITED STATES PATENT OFFICE

JOSEPH F. MOODY, OF TULSA, OKLAHOMA

OIL-WELL APPARATUS

Application filed November 16, 1928. Serial No. 319,968.

My invention relates to improvements in oil well apparatus and particularly to elevators such as are used for manipulating the drill or string of tubing in the well hole.

5 An important object of the invention is to provide a novel detachable wear plate against which the tubing bears and by which it is supported.

Another object of the invention resides in 10 the provision of closure elements or dogs for the elevator opening and which are held in place by a detachable wear plate, which supports the tubing.

A further object of the invention resides 15 in the provision of a novel wear plate for elevators and which is adapted to be detachably held in place by the pivot pins which secure the elevator bail to the elevator body.

A still further object of the invention is 20 to provide a device of this character which is relatively simple in construction, inexpensive of manufacture and highly efficient in practical use.

The invention also resides in certain novel 25 features of construction and combination of the various parts and in modes of operation as hereinafter described and claimed, reference being had to the accompanying drawing which illustrates the now preferred embodiment of the invention.

It is to be understood that the invention is capable of various modifications within the spirit and scope of the subject matter claimed.

In the drawing, wherein the same reference characters have been used to designate 30 the same parts in all views,—

Figure 1 is a top plan view of an elevator incorporating my invention;

Figure 2 is a similar view with the novel 40 wear plate removed so as to expose the dogs and guide-means therefor;

Figure 3 is a cross sectional view taken on the line 3—3 of Figure 1, and

Figure 4 is a group perspective view illustrating the wear plate and other associated 45 elements.

Referring specifically to the drawing, the elevator comprises a body 5 which is provided at opposite sides with ears 6, which are 50 horizontally slotted, as at 7, to receive the

bails 8 which connect the elevator to the hoisting apparatus.

The bails 8 are secured in the ears 7 by means of pivot pins 9,—it being observed that each pivot pin 9 has a cotter pin 10 extending 55 transversely therethrough and adjacent the inner exterior surfaces of the ears 6. The novel wear plate 16 cooperates in holding the pivot pins 9 in fixed position, as will be presently explained.

Referring now to Figure 2, it will be noted that the top surface of the elevator body 1 is provided with a circumferential groove 11, which is enlarged at the front of the elevator as at 11^a on either side of the work receiving 60 slot 12. The groove 11 and slot 12 define the central boss-like member 13, which as viewed in Figure 2 has the appearance of a fairly full moon.

The dogs 14 have their intermediate portions semi-circular, as shown in Figures 2 and 4. The forward ends of these dogs are provided with enlarged nose portions 14^b working in the groove enlargements 11^a. The rear ends of the dogs are provided with somewhat laterally off-set handles 14^a. Figure 2 also shows that the groove 11 receives a coil spring 15. It is believed to be obvious that said spring bearing against the shoulders 14^d serves to separate the handles 14^a and thus 70 urge the nose portions 14^b of said dogs into engagement, as shown in Figure 1. Adjacent the shoulder 14^d the handle portion of each dog has a notch 14^c so as to accommodate the flange 5^a, which constitutes the outer wall of 75 the slot 11, as best indicated in Figure 2. Thus, the bottom surface of the handle portion 14^a will make a flat contact with the rearwardly extending shelf 5^b of the body, as seen in Figures 1 and 2.

The novel wear plate 16, which has been referred to incidentally hereinabove, is best shown in Figure 4. It is noted that the central portion of this wear plate is considerably thickened so as to provide a maximum strength at the point of contact by the work adjacent the slot 16^a which matches with the slot 12 of the body 5. The end of the wear plate 16 opposite the slot 16^a is indicated at 16^b. As shown, the portion 16^b is adapted to 80 85 90 95 100

overlie the rear ends or handle portions 14^a of the dogs 14, so as to protect the same against injury. In other words, the handle portions 14^a of the dogs are slidingly confined between the shelf portion 5^b of the body and the rear extension 16^b of the wear plate.

Referring to Figures 3 and 4 it will be noted that the wear plate 16 has its thickened portion provided with outwardly tapered grooves 17 of arcual cross sections. These grooves 17 are adapted to receive the ends of the pivot pins 9, as best indicated in Figure 3. Manifestly, the pivot pins 9 bearing against the wear plate 16 and more specifically bearing against the grooves 17 thereof will confine the wear plate in place and thus hold the dogs 14 and springs 15 in assembled relationship with the body 5.

When it is desired to remove the wear plate to replace a dog 14, the spring 15 or to substitute a new wear plate for a worn one, it is only necessary to remove the cotter pins 10. This having been done it is perfectly obvious that the pivot pins 9 can be moved outward so as to clear the sides of the wear plate 16. The wear plate 16 is thus freed for removal. It is desired to direct attention to Figure 4 wherein the wear plate 16 is provided with shallow notches 17^a at the outer ends of the grooves 17. The purpose of this is to enable the wear plate to be removed without necessitating actuation of the pivot pins 9 so as to completely clear the inner exterior surface of the ears 6. Furthermore it is quite advantageous to have the ends of the pivot pins extend slightly beyond the inner exterior surface of the ears 6, so as to act as a guide when the wear plate is being put in place. More specifically, the notches 17^a and pins 9 serve to guide the wear plate into proper position upon the body 5 of the elevator. This is quite an important item, since the wear plates 16 will be of considerable size and weight.

The device is the essence of simplicity and its advantages will be readily appreciated by those skilled in the art.

Having thus described my invention, what I claim as new and desire to secure by Letters Patent is:

- 50 1. The combination with an elevator; of a detachable wear plate, removable bail attaching pins, and said pins being adapted to overlie said wear plate to hold the same in place.
- 55 2. In a device of the class described, a body having a work receiving opening, closure means for said opening, said body having a surface recess for receiving said closure means, a detachable wear plate for holding said closure means and body assembled, and bail-holding pivot pins adapted to engage said wear plate to hold the same in place.
- 60 3. In a device of the class described, a body having a work receiving opening, closure means for said opening, said body having a

surface recess for receiving said closure means, a detachable wear plate for holding said closure means and body assembled, bail-engaging pins removably carried by said body, said pins being adapted to overlie said wear plate to hold the same in place, and said wear plate having a portion defining an abutment to limit movement of said pins in one direction.

4. In a device of the class described, a body having a work receiving opening, closure means for said opening, said body having a surface recess for receiving said closure means, a detachable wear plate for holding said closure means and body assembled, bail-engaging pins removably carried by said body, said pins being adapted to overlie said wear plate to hold the same in place, and said wear plate having a portion defining an abutment to limit movement of said pins in one direction and stop elements carried by said pins for limiting movement of the same in the opposite direction.

5. In a device of the class described, a body having a work receiving opening, duplicate dog members providing a closure for said opening, said body having a surface recess for receiving said closure dogs, a detachable wear plate for holding said closure and body parts assembled, and a coil spring in said recess and bearing against said dog members for normally holding the same in a position to close the work receiving recess of said body.

6. The combination with an elevator body having a detachable wear plate and bail carrying ears; of a member carried by one of said ears and movable to lock said plate upon said body.

7. The combination with an elevator body having a detachable wear plate and bail carrying ears; of members carried by said ears and movable to lock said plate upon said body.

8. The combination with an elevator body having a detachable wear plate and bail carrying ears; of members carried by said ears and movable to lock said plate upon said body, and said wear plate having guide and seating portions cooperating with said members.

9. The combination of an elevator body and removable wear plate, one of the same having guide notches in opposite sides and the other having movable lugs adapted to enter said notches whereby to guide the body and wear plate to assembled position, and keeper recesses communicating laterally from said guide notches and into which said lugs are adapted to be actuated to lock the body and wear plate together.

In testimony whereof I affix my signature.

JOSEPH F. MOODY.
